UNITED STATES PATENT OFFICE.

CHARLES A. BUTTERWORTH, OF MCCOMB, MISSISSIPPI.

ANTIBALLOON DEVICE FOR COTTON-SPINNING MACHINES.

Application filed May 8, 1926. Serial No. 107,729.

This invention relates to improvements in attachments for cotton spinning machines, particularly in an anti-balloon device for ring spinning frames and filling 5 wind twister frames.

An object of this invention is to provide means for materially increasing the production of a cotton spinning machine by being able to run the machine at a high speed, 10 thereby functioning to avoid waste due to less end breakage, the use of lighter yarns, and less twist required in the yarn. This invention operates to produce better and more even yarn, and is considerably less injurious to the product within the regular separators, principally due to the possible use through this invention of the lighter travellers.

Further objects of this invention are to 20 provide a device which will be particularly advantageous when attached to narrow gauge frames, and other suitable types of machinery commonly used in the spinning of cotton. Further advantages of this invention are its low first cost and practically no upkeep expense.

A further object of this invention is to 30 provide a means which will allow a uniform weight of travellers on frames having different conditions of rings, but on the same counts.

Further objects of this invention will appear from the following detailed description of the device, and in the disclosure in the 35 single sheet of drawings which is herewith made a part of this application.

In the drawing,

Fig. 1 illustrates a vertical, longitudinal view of a portion of a cotton spinning machine, showing a series of spindles located in the ring rail of the machine, and the balloon arrestor rod together with its supports.

Fig. 2 represents a vertical sectional view of Fig. 1, taken along line 2—2.

Fig. 3, represents a horizontal view of a portion of the arrestor rod having adjustably attached thereto, a series of uprights adapted to adjustably support the arrestor rod upon the ring railing on the spinning machine.

Numeral 1 designates the ring rail of a cotton spinning machine, adapted to have suitably positioned thereon, a series of rings 2, adapted to carry spindles 3. An apron 55 portion 4 may be attached along the front edge of the ring rail 1, while suitably posi-

tioned along the inner longitudinal edge of the ring rail 1, are a series of upright elements 5 made of any suitable material and bent into an approximate hooked form in 60 order to allow them an inwardly projecting guide portion 6. One end of the element 5 is adapted to be threaded as at 7, and supplied with adjusting nuts in order to adjust the element 5 for height on the ring rail 1, 65 this adjustability may be accomplished by adjusting nuts 8 and 9 cooperating with the threaded portions 7, extending through a suitable opening in the ring rail 1, as at 10. The upper end of the supporting element 5 70 is adapted to have loosely and adjustably mounted thereto a detachable element 11, preferably made from a suitably formed piece of metal having openings therein as at 12 and 13, the end of the supporting element 75 5 being adapted to be inserted in the opening 13 in loose relationship thereto, while the other opening in the element 11 is adapted to receive the balloon arrestor rod 14 in slide- 80 able relationship thereto. It is apparent 85 from this arrangement that the arrestor rod 14 when positioned in the opening 12 will be approximately at right angles to the projecting supporting element 5, the end of which extends through the opening 13 in the element 11 just beneath the arrestor rod 14. After desired adjustment has been 90 made of the arrestor rod 14 in relation to supporting element 5, interlocking means 15, comprising an adjustable set screw 15 95 may be applied, and the supporting element 5 and the arrestor rod 14 be clamped into 100 position.

In operation, this invention provides a device consisting preferably of three adjustable uprights to each ring rail section, although it is to be understood that a plurality of these uprights may be utilized without in any way affecting the merits of this invention. The uprights are so positioned in the 100 ring rail of the machine, that they may be adjusted for height above the ring rail, and also adjustable to distance from the center of the spindles to accommodate the balloon beneath the spindles and the elements 6 of 105 the upright.

This invention provides an adjusting feature, which will enable a cotton spinning machine of a suitable type to greatly increase its production, owing to the possible 110 use of higher speeds, thereby functioning to produce less waste, there being less end

breakage. Lighter travellers may be used in the machine and considerable less twist will be required in the yarn.

What I claim is:

5. 1. In a cotton spinning machine having a balloon arrestor rod, a spindle, a ring rail, an upright support, a detachable rod holding element loosely and adjustably mounted on the upright support for adjusting the 10 distance from the spindle to the arrestor rod.
15. 2. In a cotton spinning machine having a balloon arrestor rod, a spindle, a ring rail, an upright support, a detachable rod holding element loosely and adjustably mounted on the upright support for adjusting the distance from the spindle to the arrestor rod, means for adjusting the height of the 20 arrestor rod above the ring rail.
25. 3. In a cotton spinning machine having a balloon arrestor rod, a spindle, a ring rail, an upright support, a detachable rod holding element loosely and adjustably mounted on the upright support for adjusting the distance from the spindle to the arrestor 30 rod.
35. 4. In a cotton spinning machine having a balloon arrestor rod, a spindle, a ring rail, an upright support, a detachable rod holding element loosely and adjustably mounted on the upright support for adjusting the distance from the spindle to the arrestor 40 rod, means for adjusting the height of the arrestor rod above the ring rail, the rod holding element being adapted to receive in 45 a slidably loose relationship both the rod and the upright support in such a manner that they may be clamped in position by means of a tension element.

In testimony whereof I affix my signature.

CHARLES A. BUTTERWORTH.
